ATTORNEY

UNITED STATES PATENT OFFICE.

FREDRIC O. GRAF, OF SAN FRANCISCO, CALIFORNIA.

KNOCKDOWN CABINET FOR AUTOMOBILES.

1,337,449.

Specification of Letters Patent.

Patented Apr. 20, 1920.

Application filed April 16, 1919. Serial No. 290,603.

To all whom it may concern:

Be it known that I, FREDRIC O. GRAF, a citizen of the United States, and a resident of the city and county of San Francisco, 5 State of California, have made a new and useful invention—to wit, Improvement in Knockdown Cabinets for Automobiles; and I do hereby declare the following to be a full, clear, concise, and exact description of 10 the same.

This invention relates to a new and useful improvement in automobile cabinets of the knock down type.

One of the objects of this invention is 15 to produce a cabinet adapted to be carried on the running board of an automobile, and one which may be knocked down or taken apart to form other objects.

Another object of this invention is to 20 produce a cabinet which may be used by camping parties to serve as a table and benches and when folded may be used as a storage receptacle.

Another object is to produce a cabinet 25 which may be manufactured from any light material, and one which may be fashioned without the employment of expensive special machinery.

In this specification and the annexed 30 drawings, the invention is illustrated in the form considered to be the best, but it is to be understood that the invention is not limited to such form, because it may be embodied in other forms, and it is also to be 35 understood that in and by the claims following the description, it is desired to cover the invention in whatsoever form it may be embodied.

In the drawings forming a part of this 40 specification,

Figure 1 is a cross section of Fig. 2 taken on the line X—X showing the parts within the cabinet.

Fig. 2 is an end view of my cabinet.

Fig. 3 is a top plan view thereof partly broken away.

Fig. 4 is a sectional detail view taken on the line 4—4 of Fig. 3.

Fig. 5 discloses my cabinet in knocked 50 down position and forming a table and two benches.

Fig. 6 is a perspective view of an automobile with my cabinet attached to one of the running boards thereof.

55 Referring more in detail to the drawings, the numeral 5 designates the cabinet as a

whole. This cabinet is rectangular in shape and resembles a box structure having a top 6 and a bottom 7. Rigidly attached to the top section 6 are two side members 8 and 9. Attached to the bottom member 7 are two side members 10 and 11. The top member 6 is formed of two sections and hinged at 12, as shown in Fig. 3. The top 6 and side supports 8 and 9 or bottoms 7 and supports 10 and 11 form individual benches. 60

If desired, a fabric may be fastened to the top members by a bead 13. This fabric may be of leather, oilcloth, or any suitable material which will prevent rain and dust 70 entering at the point 14.

In the side members 8 and 9, 10 and 11, I form grooves 15 and 16, which grooves accommodate the edges of the front and back of the cabinet 17 and 18. These last 75 mentioned members have legs 19 and 20 attached thereto through braces 21 and 22 hinged to said members 17 and 18. The front 17 and legs 19 or back 18 and legs 20 form individual tables when in operative 80 position.

To keep the parts assembled, I provide a strap 23 passing through retainers 24 suitably placed upon the sides 8 and 9, 10 and 11. The ends of this strap are attached to 85 the running board in any suitable manner.

The sides of the cabinet are provided with cleats 25 and 26, which cleats carry shelves 27 and 28.

Assuming that the cabinet is attached to 90 the running board, and it is desired to disassemble the same, the forward part of the top 6 is raised, as shown in Fig. 4. The member 18 may then be withdrawn as the same is free to slide in the grooves 15. 95

Upon the withdrawal, the legs carried thereon may be unfolded by swinging the brace members 21 and 22 to a vertical position, as shown in Fig. 5. Suitable fasteners, such as hooks 29, are provided to retain these legs in extended position. Thus far it will be seen that the cabinet front has been removed. This gives access to the shelves 27 and 28 which may be employed for the transport of commodities such as 105 luggage, food and utensils. The shelf 27 is now removed and the top 6 with its depending members 8 and 9 is removed which form a bench, as indicated at 30 in Fig. 5. The rear of the cabinet is then removed 110 which forms the remaining table, also shown in Fig. 5. The bottom 7 and members 10

and 11 are then turned over and set upon the ground, as shown at 31 in Fig. 5, and this forms the other bench.

If desired, the shelves 27 and 28 may be 5 rigidly attached to the cleats 25 and 26. This will be an additional brace for the benches when they are being used as seats.

In Fig. 3 I have shown a receptacle 32 adapted to contain ice for preserving the 10 contents of the cabinet.

Having thus described my invention, what I claim as new and desire to secure by Letters Patent is:—

1. A device of the character described, 15 comprising individual, front and back sections; a bottom section having upstanding end members and grooved on the inner sides thereof to receive said front and back sections; a top section with depending side 20 members thereon and grooved on the inner faces thereof, adapted to slidably engage the front and back sections.

2. In a device of the character described, 25 the combination of a top section having depending side members thereon; a bottom section having upwardly extending side sections attached thereto; continuous grooves in said side sections and said top and bottom sections and individual front and back 30 sections adapted to rest within said continuous grooves.

3. In a device of the character described, 35 the combination of a top section having depending side members thereon; a bottom section having side sections attached thereto; continuous grooves in said side sections and said top and bottom sections; individual front and back sections adapted to rest 40 within said continuous grooves, and said top section having a hinged portion overlying said front section.

4. In a device of the character described, 45 the combination of two individual bench seats with supporting members thereon; grooves in the inner sides of said supporting members and under faces of said bench seats; two individual table sections adapted to slidably fit within said grooves, said individual bench seats and supporting members 50 forming respectively the top, bottom and sides of a box when assembled and the

table sections forming a front and back thereto.

5. A knock down cabinet consisting of two individual tables forming the front and back thereof; two individual bench seats with supporting members thereon having grooves on the inner sides of each of the supporting members and under faces of each of the bench seats, to receive said front and back sections and hold the same slidably therein, said bench seats and supporting members forming respectively the top, bottom and sides of the cabinet.

6. A knock down cabinet consisting of 65 two individual bench members each comprising a seat and a pair of supports and forming respectively the top, bottom and sides of a cabinet; continuous grooves on the inner sides of the supporting members and under faces of the bench members of each of the individual benches; table members adapted to slidably fit within said grooves and forming a front and back on said cabinet and a hinged portion on one of said bench seat 75 members adapted to overlie and engage the edge of one of the table members.

7. In a device of the character described, 80 the combination of a top section, depending side members thereon, a bottom section, side sections attached thereto, continuous grooves in said side sections and said top and bottom sections, a front and back section adapted to rest within said continuous grooves, said top section having a hinged portion overlying 85 said front section, and folding legs carried by said front and back section.

8. In a device of the character described, 90 the combination of a top section having depending side members thereon; a bottom section having side sections attached thereto, means on the inner faces of the top and bottom sections for receiving front and back sections, said top section having a hinged portion overlying said front section and 95 folding supporting members carried by the front and back sections.

In testimony whereof, I have hereunto set my hand at San Francisco, California, this 4th day of April, 1919.

FREDRIC O. GRAF.
